INSOLE MACHINE

Frederic E. Bertrand, Lynn, Mass., assignor to
United Shoe Machinery Corporation, Flemington, N. J., a corporation of New Jersey

Application March 8, 1941, Serial No. 382,399

59 Claims. (Cl. 12—20)

This invention relates to machines for use in the manufacture of insoles and particularly to machines for forming and attaching to the marginal portion of an insole a ribbed strip to prepare the insole for use in the manufacture of welted shoes.

An object of the invention is to provide novel and effective means for forming the composite strip disclosed in Letters Patent of the United States No. 2,288,448 granted June 30, 1942, upon an application of Stanley M. Griswold, into a strip having a sewing rib.

Another object of the invention is to provide novel and effective means to apply the formed strip to the margin of an insole to provide an insole having a sewing rib to which an upper or an upper and a welt may be attached.

A further object of the invention is to enable the strip-forming and strip-applying operations to be performed simultaneously.

The illustrated machine is supplied with a composite strip comprising a plurality of layers secured together along their longitudinal central portions and it comprises means for turning the marginal portions of one of the layers toward each other as the strip is fed and means for feeding the strip and pressing the folded margins together. When the composite strip consists of three layers one of which is narrower than the others, the machine operates to fold the marginal portions of the intermediate strip and of the narrow strip toward each other, the outer marginal portions of the wider strip being brought together to enclose the folded narrower strip which thus constitutes a rib reinforcement. The machine comprises also means for introducing between the margins which are folded toward each other a core piece or cord, if desired, in position to be embraced by the margins as they are being folded and to constitute a reinforcement for the rib so formed.

From the strip-forming mechanism, the strip is conducted to strip-applying mechanism comprising a support for the insole body which may, for example, consist of a table arranged to rotate in a horizontal plane, an edge gage for the sole, a strip guide to receive the ribbed strip, means for imparting a four-motion movement to the strip guide, strip-feeding means carried by the strip guide, and insole-feeding means also carried by the strip guide. Thus the formed strip and the insole are fed simultaneously.

To cause cement on the strip to adhere to cement on the insole, means is provided for pressing the marginal portions of the unfolded

layer of the strip against the surface of the marginal portion of the insole, which means preferably applies continuous rolling pressure to the outer marginal portion of the strip and intermittent pounding pressure to the inner marginal portion, the pressure in both cases being applied yieldingly.

In order to apply the strip satisfactorily about a sharply curved portion of the insole such as the toe, it is desirable to provide fullness in the strip, particularly its inner marginal portion. This is effected in the illustrated machine by providing means for feeding the strip faster than the insole is fed, the result being that slight wrinkles are formed in the inner marginal portion of the strip which are not sufficient to form folds and are beaten flat by the action of a hammer which acts subsequently upon them. As illustrated, the fulling of the strip is effected by means for causing more of the movement of the feed stroke to be imparted to the strip than is imparted to the insole; that is, the insole-feeding means engages the insole only after a part of the feed movement has been imparted to the strip guide.

The strip-forming mechanism and the strip-applying mechanism are arranged to be operated in unison to cause the strip to be formed at approximately the same rate that it is applied to the insole.

These and other features of the invention will appear more fully from the following description when read in connection with the accompanying drawings and will be pointed out in the appended claims.

In the drawings,

Fig. 1 is a front elevation, partly in section, of a machine embodying the invention;

Fig. 2 is a perspective view of means for folding the marginal portions of one portion of the strip toward each other;

Fig. 3 is a view similar to Fig. 2 with the parts arranged for introducing a reinforcing element such as a cord between the folded portions;

Fig. 4 is an elevation of the machine taken from the right-hand side;

Fig. 5 is an elevation of the head of the machine taken from the left-hand side;

Fig. 6 is a plan of an insole produced by operation of the machine;

Figs. 7 and 8 are details in plan of parts shown in Fig. 2;

Fig. 9 is a plan view, partly in section, of parts shown in Fig. 1;

Fig. 10 is a detail of ratchet and pawl mechanism for feeding the strip;

Fig. 11 is a perspective detail of the strip guide, the strip-feeding and the insole-feeding means;

Fig. 12 is an elevational detail of parts shown in Fig. 11;

Fig. 13 is a detail, partly in section, showing the relation of the strip to the strip-feeding means and strip guide while the strip is being fed;

Figs. 14, 15 and 16 are fragmentary elevations illustrating various positions of the parts during the operation of feeding the insole and fulling the strip; and

Figs. 17, 18, 19 and 20 are perspective views of various forms of composite strips which may be formed and/or applied to insoles by the machine of this invention.

The illustrated machine may be used to apply or to form and apply ribbed strips of either of the types represented in Figs. 17, 18, 19 and 20. Each of the strips comprises a base layer 20 and a rib-forming layer 22 attached by stitches 24 to the layer 20 along its longitudinal central portion, the marginal portions of the layer 22 being adapted to be folded toward each other to form a sewing rib 26 (Fig. 17). The layer 22 may be made wider and have a fold 32 formed therein so that when the marginal portions of the layer 22 are brought together the fold 32 will be included between them and form a rib reinforcement (Fig. 20) or the strip 22 while still flat may have secured thereto at its central portion a narrower strip 30 so that when the marginal portions of the strip 22 are brought together the strip 30 will be folded to form a reinforced rib, as shown in Fig. 18. Rib strips constructed in any of these ways have proven most satisfactory and make unnecessary the introduction of separate core material for reinforcing. However, if desired, a reinforcing member such as a cord 28 may be introduced and the marginal portions of the layer 22 brought together to enclose the cord (Fig. 19).

Strips of any one of the types mentioned may be preformed and wound upon a reel before being presented to the machine. In this case it is convenient in winding the strip upon the reel to fold the rib portion flat against the base portion 20 before it is so wound.

In applying a strip thus prepared, for example of the type shown in Fig. 18, it is led from a reel 40 (Fig. 4) to a guide roll 42 at the top of the machine, the guide roll being rotatably mounted on a pin 44 carried by a member 46 pivoted at 48 to a fixed bracket 50 secured at 51 to an arm 52 fixed at 53 to a head frame 54. The guide roll 42 may be swung upward about the pivot 46 to facilitate threading the strip into the machine and is yieldingly held in operative position by a spring clip 56 (Fig. 4). A guard 58 extends across the roll to prevent accidental displacement of the strip, the guard being secured at 60 to the member 46. From the roll 42 the strip is led through a guide 62 (Figs. 2 and 7) which embraces the marginal portions of the base layer 20 and is carried by a stud 64 which enters a hole in the fixed arm 52 and is held therein by a set screw 65 (Fig. 1).

Below the guide 62 (Fig. 2) is a plow 68 arranged to turn one marginal portion of the layer 22 to a position nearly at right angles to the layer 20 and on the opposite side (Fig. 8) is another plow 70 enantiomorphously arranged to turn the opposite marginal portion of the strip 22 toward the first marginal portion. The plows 68, 70 and 75

a spacing block 71 are secured by screws 72 to a block 74 fixedly secured to the stud 64.

Assuming that the strip on the reel is preformed and has its rib 26 lying flat against one margin of the base layer 20, the base layer of the strip is passed through the guide 62, the rib 26 being raised by engaging the inner face of one of the plows, for example the plow 68, which causes the rib to be progressively raised as the strip passes through another guide 75 similar to 62 and engages a cylindrical roll 73 (Fig. 9) mounted on a stud 78 secured at 80 to the bracket 50. At the point where the base layer 20 is engaged by the roll 76 the rib portion 26 of the strip passes between a pair of rolls 82, 84 which have a portion of their peripheries reduced at 86 to engage the reinforced portion of the rib 26 and have unreduced portions 88 to engage the part of the rib which is beyond the reinforcement. The reduced portions 86 are preferably roughened to assist in feeding the strip and the rolls are driven in opposite directions to feed the strip by a gear 90 on the hub of the roll 82 which meshes with a similar gear 92 on the hub of the roll 84. The gear 90 is keyed to a shaft 94 journaled in the arm 52 and having fixed to its rear end (Fig. 4) a ratchet wheel 96.

The roll 84 (Fig. 1) and its gear 92 are loosely mounted on a stud 98 fixed in a lever 100 pivoted on a pin 102 which is secured at 104 (Fig. 4) in a hole provided in the bracket 50. Integral with the hub of the lever 100 is an arm 106 which carries a stop screw 108 arranged to engage the end of the stud 78 (Figs. 1 and 9) to limit approaching movement of the rolls which are urged toward each other by a spring 110 (Fig. 1) connected at one end to a pin 112 on the lower end of the lever 100 and at the other end to a pin 114 on the fixed arm 52. The arm 106 is provided with a handle 116 by upward movement of which the rolls may be separated against the spring 110 to permit introduction of the strip between them.

Returning now to the mechanism for operating the rolls, the shaft 94 to which the ratchet wheel 96 is secured has loosely mounted thereon a sleeve 118 (Fig. 10) carrying an arm 120 to which is pivoted at 122 a pawl 124 to engage the ratchet wheel 96. The pawl has an arm 126 connected by a tension spring 128 to a pin 130 on the arm 120. One end of a link 132 is pivoted at 134 to the arm 120 and the other end (Fig. 1) has a pivot 136 adjustable lengthwise of a slot 138 in an arm 140 secured to a rockshaft 142. Projecting downwardly from the rockshaft 142 and secured thereto is an arm 144 to which is pivoted at 146 the upper end of a connecting rod 148 which carries an eccentric strap 150. The strap embraces an eccentric or cam 151 (Fig. 4) secured to a shaft 152 journaled in the frame 54 and arranged to be driven by a pulley 154 from any suitable source of power.

The strap 150 is formed with a gib or tongue 156 engaging a slideway 158 formed in a disk 160 secured to the frame 54 in which the shaft 152 is journaled. The slideway 158 extends in a straight line directed toward the pivot 146 (Fig. 1) of the connecting rod 148 and the strap 150 has surfaces at right angles to the slideway for engagement with the cam or eccentric 151 so that the motion imparted thereby to the rod 148 will be only a to-and-fro motion in the direction of the slideway 158. The tendency of the slight circular movement which the pivot 146 has about its center 142 to cramp the tongue 156 in the slideway 158 is obviated by a slight

looseness in the fitting of the parts. This construction avoids vibration by eliminating the unused motions imparted to the eccentric strap by the usual construction.

From the rolls 82, 84 the strip is carried to a strip guide which, as shown in Figs. 11 and 12, comprises a casing 170 having side walls and a bottom 172, the casing being open at the front and rear and having an opening 174 in the bottom 172. The casing 170 embraces a block 176 and a spacing block 178 which occupies the space in the casing not used in the construction shown. On the upper side of the block 176 is a dovetail rib 180 which engages a dovetail groove in the lower end of a strip guide carrier 182. The carrier is split at 184 and provided with a clamping screw 186 to bind the rib 180 upon the carrier. One side of the casing 170 is secured to the block 176 by a screw 188 and the other side of the casing is secured to the block 176 by a screw 190 which passes through the spacing block 178 into the block 176. The block 176 has a groove 192 to receive the rib 28 of the strip and its lower end is spaced a sufficient distance from the bottom 172 of the casing to provide a space 194 (Fig. 12) for the passage of the base layer 20 of the strip.

Arranged at each side of the groove 192 with their ends adjacent to the opening 174 in the bottom of the casing is a pair of feed fingers 196, 198. The fingers are both secured to a shaft 200 journaled in ears 202 extending from the side walls of the casing 170, and the finger 196 is provided with an upper arm 204 by which the fingers may be raised against the tension of a spring 206 connected between pins, one on the arm 204 and the other on the block 176. It will be understood that the feed fingers 196, 198 engage the base layer 20 of the strip on opposite sides of the rib 28 and press it against a corner 205 of the opening 174 (Fig. 13), the ends of the fingers pressing the base layer 20 slightly into the opening and binding the layer against the corner 205, thus causing the strip to be fed when the corner is moved to the left and permitting the strip to slip under the fingers when the corner is moved in the opposite direction.

The bottom 172 of the casing carries a feed foot 210 which is operated to engage the insole and to feed it at the same time that the strip is fed.

The carrier 182 has a cylindrical portion arranged to slide up and down in a bearing 300 (Fig. 1) on a yoke 302 and a reduced portion 304 carrying a sleeve 306, which sleeve fits another bearing 308 on the yoke 302. The reduced portion 304 of the carrier has slidably arranged thereon two oppositely disposed flanged sleeves 310, 312 between the flanges of which is a compression spring 314. The flanged sleeve 312 bears against the upper end of the enlarged portion of the carrier and the sleeve 310 engages the lower end of the sleeve 306 which is prevented from rotation by a pin 316 mounted in a groove in the yoke 302 and engaging a flat surface on the sleeve 306. The upper end of the sleeve 306 projects beyond the bearing 308 and is threaded to receive lock nuts 318 the upper one of which engages a block 320 pivoted by a pin 322 to bifurcations of an arm 324 fixed to the rockshaft 162. The reduced portion 304 of the carrier extends through the block 320 and through one side of the pin 322, to prevent withdrawal of the pin, and the upper end thereof carries two set nuts 326 threaded thereon. With this construction it will be seen that upward movement of

the arm 324 will positively raise the carrier 182 and that downward movement of the arm will depress the sleeve 306 and, acting through the spring 314, will yieldingly depress the carrier 182.

5 The yoke 302 is operated to impart to-and-fro or feed movements to the carrier. For this purpose the yoke has mounted for horizontal sliding movement therein a block 328 which is engaged by a pin 330 mounted eccentrically on the shaft 162. On the outer end of the pin 330 is a clamp collar 332 (Fig. 4) holding the block and yoke in place. The block 328 has a stem 334 extending through a retaining plate 336 held by screws 338 to a face on the yoke 302. The plate 336 is 10 counterbored to receive a compression spring 340 one end of which rests against the block 328 and the other end against the plate. The stem 334 extends far enough beyond the plate 336 to receive a collar 342 and a nut 344. It will be seen that the nut 344 limits movement of the block 20 in response to the spring 340 and that if movement of the yoke 302 to the right is arrested the spring 340 will yield. Mounted in a recess in the yoke 302 is a bifurcated block 346 between the 25 ears of which is pivoted a roll 348, and on an arm 350 fixed to the frame is mounted a cam block 352 in position to be engaged at times by the roll 348. To prevent turning of the cam block 352 if it is fitted between vertical surfaces on the arm 350 and, to enable it to be adjusted horizontally, has a threaded stem 356 which passes through holes in two parts 357, 358 of the arm 350 and has threaded thereon a knurled nut 360 located between the parts 357, 358 of the arm 350 and on the outer side of the part 359 has a nut 362 so that the cam block 352 can be adjusted toward and from the roll 348 by manipulating the nuts 360, 362.

30 The yoke, of course, receives up-and-down and to-and-fro movements from the eccentric pin 330, the to-and-fro movements imparting similar movement to the carrier 182, the up-and-down movements not being utilized to move the carrier.

35 The cam block 352 (Fig. 1) has at the left a cam face 364 the upper part of which is farther to the right than the lower part. During the orbital movement of the roll 348, due to the action of the eccentric pin 330 on the yoke 302, the roll will first engage the upper part of the cam face, the spring 340 being, if necessary, compressed. This engagement of the roll with the cam determines the movement of the feed fingers toward the right and hence the amount which the strip will be fed when the fingers move toward the left. As the orbital movement of the yoke 302 continues, the roll 348 will move downwardly and engage the lower portion of the cam face and be moved toward the left, causing further compression of the spring 340. This occurs before the feed foot 210 engages the insole and hence the insole will be fed a less distance than the strip is fed. The timing of the parts is such that the arm 324 on the rockshaft 162 will be operated to depress the carrier 182 and hence the feed foot 210 after the roll 348 has engaged the lower portion of the cam face 364 on the cam block 352. The portion of the left-wise movement of the yoke 302 which occurs after the feed foot 210 engages the insole is utilized to feed the insole.

40 The insole is supported on a rotary table 366 with its edge against an edge gage 368 (Figs. 1 and 4). The edge gage and the table have in general the construction disclosed in Letters Pat.

ent of the United States No. 984,772, granted February 21, 1911, on application of W. C. Meyer. The table 366 is free to rotate on ball bearings 370 and is normally in a lowered position. A sleeve 372 in which the table is mounted to turn is provided with a clamp collar 374 on which is journaled a shaft 376. On the shaft 376 is an arm 378 to the end of which is pivoted at 380 a link 382 the upper end of which is pivoted at 384 to a fixed bearing 386 in which the sleeve 372 slides. The arm 378 and link 382 constitute an inverted toggle. With the parts in the position shown in Fig. 1, counterclockwise movement of the shaft 376 will raise the table 366. The arm 378 has an extension 388 which is connected by a chain 390 to a treadle lever 392 by depression of which the toggle may be straightened to raise the work support. To insure that the toggle will be broken when the treadle is released, a tension spring 394 is connected between the arm 388 and a lug 396 on the machine frame.

The edge gage 368 is adjustable toward and from the front of the machine to vary the location of the ribbed strip relatively to the edge of the insole, the strip, as shown in Fig. 6, being preferably located at three different distances from the edge of the insole as indicated at A, B and C. The edge gage is provided with a toothed shank 400 (Fig. 4) engaged by a segmental gear 402 fixed to the upper end of a rockshaft 404 which is journaled in a bracket 406 adjustably mounted on a lateral projection 407 of a collar 408 secured to the upper end of the work-table-supporting sleeve 372. The bracket 406 is provided with a horizontal shank 409 engaging a slot in the lateral projection 407. The shank 409 is adjustably fixed in position by means of a vertical screw 410 passing through a slot in the shank and threaded into the projection 407. The rockshaft 404 carries at its lower end an arm 412 having a forked end engaging a block 414 pivotally mounted on a disk 415 fixed to the upper end of a rockshaft 416. The rockshaft 416 is journaled in a sleeve 418 adjustably fixed in a bracket 420 secured at 421 to the projection 407. The lower end of the rockshaft 416 carries a head or collar 422 to which is pivotally connected a hand lever 424 by which the rockshaft 416 may be turned. When the rockshaft is turned, the block 414 turns the arm 412, thereby actuating the rockshaft 404 and causing the edge gage 368 to move transversely of the ribbed strip which is being fed through the casing 170. To locate the edge gage at three different distances to provide for locating the strip, as illustrated in Fig. 6, three adjustable stops are provided. A pin 426 projecting downwardly from the disk 415 engages the bracket 420 and limits the extreme forward position of the edge gage which it occupies when the strip is being laid nearest to the edge of the insole, as shown at B (Fig. 6).

The adjustable connection between the shank 409 and the projection 407 permits adjustment of the extreme forward position as determined by the pin 426 and for this purpose an adjusting screw 428 is provided, this screw being threaded into the shank 409 and having a groove rear its head which engages a lug 430 on the projection 407. Turning of the screw 428 by its head 432 after the screw 410 is loosened will adjust the edge gage 368 forwardly and rearwardly.

The intermediate position of the edge gage is determined by a latch 434 carried by the hand lever 424 and engaging a recess 436 (Fig. 4) in the adjustable sleeve 418. The position of this

recess is adjusted by releasing a nut 438 on a clamp collar surrounding the sleeve 418 and then turning the sleeve. The latch 434 is held in engagement with the recess 436 by a spring 442 which tends normally to swing the hand lever 424 upwardly. By depressing the hand lever the operator can release the latch.

The extreme rearward position of the edge gage is determined by a lug 444 on a clamp collar 446 surrounding the disk 415 and held thereon by a clamp screw 448. When the hand lever 424 is swung to its extreme right-hand position (Fig. 4), the lug 444 engages a fixed surface to limit its movement. This rearward position may be varied by loosening the clamp collar 446 and rotating it on the disk 415. To prevent rotation of the collar 446 (Fig. 5) which carries the edge gage mechanism, a vertical pin 450 on the machine frame engages a hole in the collar.

As the base layer 20 of the strip is being fed by the fingers 196, 198 in the casing 170 and the insole by the presser-foot 210, the marginal portions of the base layer 20 are firmly pressed against the insole, the insole and the base layer being each provided with a pressure-responsive cement such as latex cement. Referring to Fig. 5, the outer marginal portion of the base layer 20 is engaged by a roll 452 pivotally mounted on a slide 454 which can yield upwardly against the pressure of a spring 456 (Fig. 1). The slide 454 is mounted in vertical ways formed in the front portion of the frame 54 and is held in place by a cover plate 458. A lug 460 projecting forwardly from the slide 454 has secured therein a rod or pin 462 which extends upwardly through an ear 464 formed on the plate 458. The spring 456 is arranged on the rod 462 between the ear 464 and adjusting nuts 466 on the lower end of the rod. The rod extends upwardly through the ear 464 and is provided with a washer and lock nuts 468 adjustably to limit downward movement of the slide 454 in response to the action of the compression spring 456. When, after placing an insole in the machine, the table 366 is raised, the roll 452 will engage the outer marginal portion of the base layer 20 and the pressure on the roll will lift the slide 454 against the tension of the spring 456 so that during operation of the machine the roll will be continuously pressed upon the outer marginal portion of the base layer 20.

To insure that the inner marginal portion of the layer 20 will be firmly secured to the insole, it is operated upon intermittently by a hammer 470. The hammer has a tongue-and-slot connection at 472 (Fig. 1) to an arm 474 and is adjustably held in place by a screw 476 passing through a slot in the hammer and threaded into the arm 474. The arm 474 is secured to a rockshaft 478 journaled in a bracket 480 which is secured to the slide 454. The bracket 480 has a tongue-and-groove connection with the slide at 482 (Fig. 5) and is adjustably held in place by a screw 484 (Fig. 1) passing through a slot in the bracket. The rockshaft 478 has secured to its left-hand end an arm 486 to which is pivoted a link 488 the upper end of which passes freely through a block 490 which has on its opposite sides trunnions that are journaled in bearings 492 formed in the arms of a yoke 494 (Fig. 5) which is pivoted by a stud shaft 496 to an arm 498 fixed to the rockshaft 478. Between the block 490 and set nuts 500 on the link 488 is a compression spring 502 the initial tension of which may be set by adjusting the nuts 500. On the upper end of the link 488 are set nuts 504 to

positively limit downward movement of the link 488 in response to the spring 502. As the arm 498 is oscillated by the rockshaft 142 the block 490 applies pressure through the spring 502 to the link 488 and swings the arm 486 downwardly and with it the arm 474 carrying the hammer 470. The hammer is thus operated in each cycle of the machine to engage and force the inner marginal portion of the layer 20 against the insole. From Fig. 5 it will be seen that the hammer 470 in its movement about the shaft 478 has, besides its heightwise movement into engagement with the inner margin of the layer 20, a component of movement toward the rib 26 and outwardly of the insole. When the machine is used to apply the form of strip shown in Fig. 19, in which a cord 28 is introduced and the strip-forming layer 22 folded about it to form the rib 26, the construction is modified as shown in Fig. 3 where the spacing block 71 is extended toward the strip 20 and provided with a hole 506 through which the cord 28 may pass. In this way the cord 28 is introduced between the partially-folded marginal portions of the rib-forming strip which are pressed together to enclose the cord by the action of the rolls 82, 84. The types of strip illustrated in Figs. 17 and 20 may be formed and applied in substantially the manner explained in connection with the type illustrated in Fig. 18.

The operator of the machine will be provided with a composite strip, for example a strip composed of two layers attached together along their longitudinal central portions by rows of stitches and having pressure-responsive cement on both exposed faces. The operator will introduce the end of the strip into the mechanism at the top of the machine, passing it over the guide roll 42 and threading it into the guides 62, as shown in Fig. 7, so that one layer of the strip will be engaged by the plows 68, 70 and its marginal portions turned toward each other, as shown in Fig. 8. The strip will then be passed through the guide 75 and introduced between the rolls 82, 84, as shown in Fig. 9. The end of the strip will then be passed through the casing 170 of the strip guide, the upstanding rib portion 26 passing through the slot 192 (Fig. 12) and the unfolded base layer 20 through the slot 194 and beneath the feeding fingers 196, 198.

The operator will be furnished with insoles such as the insole S (Fig. 6), the marginal portions of one face of the insole being coated with pressure-responsive cement such as latex cement. The operator will then place an insole on the table 309 and, if it is an insole for a left shoe as shown in Fig. 6, the edge of the insole at the point S' will be brought into engagement with the edge of the gage 368 and the handle 424 operated to locate the gage in its intermediate position with the latch 434 in engagement with the recess 436. The operator then depresses the treadle 392 to raise the work support, thus pressing the insole upwardly against the yieldingly depressed roll 452 which engages the outer margin of the layer 20 projecting to the left of the guide 170 and causes it to adhere to the insole. The machine is then started and, assuming the parts to be in the positions shown in Fig. 14, the first movement of the strip guide 170 will be toward the right, the strip being held from movement in that direction by its being stuck to the insole. Movement of the strip guide to the right is limited by engagement of the roll 348 with the cam 364, as shown in Fig. 15. As the strip guide 170 is moved downwardly by the

descent of the yoke 392, the roll 348 engages the lower portion of the cam 364 which moves the guide slightly to the left, causing a fullness in the layer 20, as indicated at 28' in Fig. 16, this occurring before the descent of the yoke 392 brings the feed foot 210 into engagement with the insole. After the feed foot engages the insole the movement of the yoke 392 to the left feeds the insole and the upwardly bowed fullness 28' of the strip to the left, the hammer 470 being, at that time lifted but the strip and insole being fed while the roll 452 is pressing continuously against the outer flange of the strip 20. At the end of a feed movement the hammer 470 is operated to press the fullled portion of the inner flange of the strip 20 firmly against the insole. It will be seen that not only the upward bowing of the strip at 28' but also the fact that the bottom 172 of the casing 170 of the strip guide lies between the strip and the insole serves to hold the strip out of engagement with the insole until it passes into the field of action of the intermittently acting hammer.

As the operator approaches the ball line he shifts the handle 424 toward him until its movement is arrested by the pin 426 and the edge gage is in position to locate the strip 20 in its closest relation to the edge of the insole, as is desirable when laying the strip around the forepart of the insole. After passing the ball line on the other side of the insole the operator will shift the handle 424 to its rearward limit as determined by the lug 444, thus positioning the strip 20 at a greater distance from the edge of the insole than at the beginning as is desirable on the outer side of the insole. When a point on the insole opposite the point S' (that is, the breast line of the insole) is reached the machine is stopped, the treadle released and the strip severed.

In forming the strip shown in Figs. 18 and 20, the parts will be arranged in the same manner as for handling the strip shown in Fig. 17, the narrow strip 30 (Fig. 18) which, as well as the layer 22, may be flat when the strip is presented to the machine, being folded upon itself as the marginal portions of the layer 22 are brought toward each other by the plows 68, 70 and pressed together by the rolls 82, 84 to enclose the folded strip 30, this action being illustrated in Figs. 7, 8 and 9. The strip illustrated in Fig. 20 is formed in a similar manner, the already formed fold 32 being enclosed by the marginal portions of the layer 22 as they are folded and brought together.

In forming the strip shown in Fig. 19, the procedure will be the same as that for forming the strip shown in Fig. 17 except that, as shown in Fig. 3, the spacing member 71 will be arranged with the hole 506 therein adjacent to the strip, the cord 28 being then introduced between the marginal portions of the layer 22 as they are being folded toward each other by the plows 68, 70.

It is to be understood that if desired strips of any of the forms shown may be preformed and wound upon a reel, the rib 26 being laid flat against the base layer 20. In this case the forming mechanism of the machine will act to turn the rib 26 into a position substantially perpendicular to the layer 20, the rolls 82, 84 acting to feed the strip between them at approximately the same rate that the strip is fed by the fingers 196, 198.

Having thus described my invention, what I claim as new and desire to secure by Letters Patent of the United States is:

1. In a machine for applying a ribbed strip to insoles to form a sewing rib thereon, the combination of a rotary table for supporting the insole, means for feeding the insole, a strip guide, means carried by the guide for feeding the strip, and means for pressing the strip on the insole. 5

2. In a machine for applying a ribbed strip to insoles to form a sewing rib thereon, the combination of a freely rotating support for the insole, a strip guide, means carried by the strip guide for feeding the strip, means carried by the strip guide for feeding the insole, and means for pressing the strip on the insole. 10

3. In a machine for applying a ribbed strip to insoles to form a sewing rib thereon, the combination of a support for an insole, means for feeding the insole, a strip guide having a slot to permit passage of the rib, means carried by the guide for feeding the strip, and means for pressing the strip on the insole at each side of the rib. 20

4. In a machine for applying a ribbed strip to insoles to form a sewing rib thereon, a support for the insole, a strip guide for presenting the strip to the marginal portion of the insole, means for imparting a four-motion feed to the strip guide, means on the strip guide for feeding the insole, and means carried by the strip guide for feeding the strip. 25

5. In a machine for applying a ribbed strip to insoles to form a sewing rib thereon, the combination of a support for an insole, a strip guide having a slot to permit passage of the rib, means carried by the strip guide for feeding a strip, means carried by the strip guide for feeding the insole, and independent means for pressing each marginal portion of the strip on the insole. 30

6. In a machine for applying ribbed strips to insoles, the combination of a rotary table adapted to support an insole, a strip guide for presenting a ribbed strip adjacent to the marginal portion of the insole, feed fingers for engaging the strip, a feed foot for engaging the insole, means for imparting a four-motion movement to said fingers and said foot to feed the work, and means for pressing opposite marginal portions of the strip against the marginal portion of the insole. 40

7. In a machine for applying a ribbed strip to insoles to form a sewing rib thereon, the combination of a rotatable support for the insole, a strip guide having a slot to permit passage of the rib, fingers carried by the strip guide for feeding the marginal portions of the strip, a feed foot carried by the strip guide for feeding the insole, means for imparting a four-motion movement to the strip guide, and means for pressing the strip on the insole. 50

8. In a machine for applying ribbed strips to insoles, the combination of a rotary table adapted to support an insole, a strip guide for presenting a ribbed strip adjacent to the marginal portion of the insole, a feed member for engaging the strip, a second feed member for engaging the insole, means including a connection between the feed members for moving said members in unison to feed the work, and means for pressing the strip against the insole. 60

9. In a machine for applying ribbed strips to insoles, the combination of a rotary table adapted to support an insole, a strip guide for presenting a ribbed strip adjacent to the marginal portion of the insole, a feed member on said guide for feeding the strip, a second feed member on said guide for engaging the insole, means for operating the guide to feed the strip and the 70

insole, and means for pressing the marginal portions of the strip against the insole. 75

10. In a machine for applying ribbed strips to insoles to form a sewing rib thereon, the combination of means for supporting an insole, means for presenting a ribbed strip for application to the insole, means for feeding the insole and strip, intermittently acting means for pressing the strip against the insole, and means for holding the strip out of engagement with the insole until the strip is engaged by the said intermittently acting means.

11. In a machine for applying ribbed strips to insoles to form a sewing rib thereon, the combination of a support for an insole, means for feeding the insole, means for feeding a ribbed strip simultaneously with the feeding of the insole, a hammer for forcing the strip against the insole, and means for guiding the insole to the hammer and for holding the strip out of engagement with the insole until engaged by said hammer. 15

12. In a machine for applying ribbed strips to insoles to form a sewing rib thereon, the combination of a support for an insole, a guide for presenting a ribbed strip for application to the insole, means for imparting a four-motion feed to the strip guide, fingers on said guide for feeding the strip, a foot on said guide for feeding the insole, means for pressing the strip against the insole to apply it thereto, and means for maintaining the strip out of engagement with the insole during the feeding of the strip and insole and until engaged by the pressing means. 20

13. In a machine for applying ribbed strips to insoles to form a sewing rib thereon, the combination of a support for an insole, a strip guide for presenting a ribbed strip for application to the insole, means for feeding the insole, means for simultaneously feeding said strip, means for pressing the strip against the insole to apply it thereto, and means for holding the strip out of engagement with the insole as the work is fed and until brought into engagement with the insole by the pressing means. 25

14. In a machine for applying ribbed strips to insoles, the combination of means for applying a strip to an insole, common means for feeding the strip and insole, and means for causing only part of the feeding movement of the common means to be imparted to the insole-feeding means while it is in contact with the insole. 30

15. In a machine for applying ribbed strips to insoles, means for supporting an insole, means for guiding a strip to the insole, means for feeding the insole, and means for feeding the strip, one of said feeding means becoming operative after part of the feeding movement of the other has taken place. 35

16. In a machine for applying ribbed strips to insoles, the combination of means for supporting an insole, means for feeding the strip and insole, means for causing the strip to be fed faster than the insole, means for causing continuous pressure to be applied on one portion of the strip, and means for applying intermittent pressure on another portion of the strip. 40

17. In a machine for applying ribbed strips to insoles, the combination of a support for an insole, a guide for presenting a strip to the insole, means carried by the guide for feeding the strip, means carried by the guide for feeding the insole, means for operating said strip-feeding and insole-feeding means simultaneously to feed the work, and means for causing the strip-feeding means 45

to feed the strip faster than the insole-feeding means feeds the insole.

18. In a machine for applying ribbed strips to insoles, the combination of means for applying a strip to an insole, common means including a four-motion mechanism for feeding the strip and the insole, and means for bringing the insole-feeding means into contact with the insole only after part of the common feed movement has occurred.

19. In a machine for applying a ribbed strip to insoles, the combination of a strip guide, strip-feeding means engaging the strip at each side of the rib as it passes through the guide, a foot on the guide to engage the insole, means for imparting a four-motion feed to the guide, and means whereby a portion only of said movement is imparted to the feed foot while it is in contact with the insole.

20. In a machine for applying a ribbed strip to insoles to form a sewing rib thereon, a support for the insole, a strip guide for presenting the strip to the marginal portion of the insole, means for imparting a four-motion feed to the strip guide, means on the strip guide for feeding the insole, means carried by the strip guide for feeding the strip, and means for causing the feeding movement imparted to the strip to be longer than the feeding movement imparted to the insole.

21. In a machine for applying a ribbed strip to insoles, the combination of a strip guide, strip-feeding means engaging the strip at each side of the rib as it passes through the guide, means for imparting a predetermined feed movement to the guide, a feed foot on the guide to engage the insole, and means for bringing the feed foot into contact with the insole after a portion of said feed movement has been imparted to the guide.

22. In a machine for applying a ribbed strip to insoles to form a sewing rib thereon, a support for the insole, a strip guide for presenting the strip to the marginal portion of the insole, means for imparting a four-motion feed to the strip guide, means on the strip guide for feeding the insole, means carried by the strip guide for feeding the strip, and means for causing the insole-feeding means to engage the insole only after part of the feed movement has been imparted to the strip guide.

23. In a machine for applying ribbed strips to insoles, the combination of a rotary table adapted to support an insole, a strip guide for presenting a ribbed strip adjacent to the marginal portion of the insole, a feed member on said guide for feeding the strip, a second feed member on said guide to engage the insole, means for imparting a four-motion movement to said guide to feed the strip and the insole, means for causing more of the feed movement to be imparted to the strip than is imparted to the insole, and means for pressing the marginal portions of the strip against the insole.

24. In a machine for applying ribbed strips to insoles to form sewing ribs thereon, means for supporting an insole, a guide for presenting a strip adjacent to the margin of the insole, means for imparting a four-motion movement to the guide, means on the guide for moving the strip only in the direction of feed, means on the guide to engage the insole during its feed movement, means for causing the insole-feeding means to engage the insole only after part of the movement of the strip has been effected to cause fulling of the strip as it is applied to the insole, and

means for pressing the strip upon the margin of the insole.

25. In a machine for applying a ribbed strip to insoles, the combination of means for feeding an insole, means for guiding a strip to the insole, strip-feeding fingers in the strip guide, a feed foot on the strip guide for feeding the insole, means for imparting a four-motion movement to the strip guide, a fixed cam, and a roll movable with the strip guide, the roll engaging the cam during downward movement of the strip guide, said cam acting to move the strip guide and feed the strip prior to engagement of the foot with the insole to feed the insole.

15 26. In a machine for applying to insoles a strip having a rib upstanding substantially in the center thereof, the combination of a support for the insole, a strip guide having a slot to permit passage of the rib, feeding means engaging the strip at each side of the rib as it passes through the guide, a foot on the guide to engage the insole, means for imparting a four-motion feed to the guide, and means whereby a portion only of said movement is imparted to the feed foot while it is in contact with the insole.

20 27. In a machine for applying a multi-ply strip to an insole, means for folding plies of the strip to form an upstanding rib, means separate from the rib-forming means for feeding the insole, for feeding the strip, and for pressing an unfolded ply of the strip upon the insole, and means for operating the folding means and said separate means in unison.

25 28. In a machine for forming and applying composite strips, comprising a plurality of layers, to insoles to form a sewing rib thereon, the combination of a folder for forming layers of the strip into a rib, a pair of rollers for drawing the strip through the folder and pressing the fold, and means for applying an unfolded layer of the strip to the marginal portion of an insole.

30 29. In a machine for applying a strip having a plurality of plies to insoles, the combination of mechanism including a folder and a pair of presser members for forming plies of the strip into a rib, mechanism independent of the rib-forming mechanism for applying another ply of the strip to the insole and for feeding the strip and insole, and means for operating said rib-forming and applying mechanisms in timed relation.

35 30. In a machine for forming and applying composite strips, comprising a plurality of layers, to insoles to form a sewing rib thereon, the combination of a stationary folder for folding one layer of the strip, a pair of driven rollers for drawing the strip through the folder and pressing the fold, means for supporting an insole, means for presenting the strip adjacent to the margin of the insole, feeding means engaging the strip, feeding means engaging the insole, means for operating said feeding means in unison, and means for pressing an unfolded layer of the strip against the insole.

40 31. In a machine for applying a two-ply strip to insoles, the combination of means for introducing a core, means for folding one ply of the strip about the core to form a rib, means for supporting an insole, means for applying the other ply of the strip to the insole, means for feeding the insole, and means for feeding the strip, said feeding means being operated in timed relation.

45 32. In a machine for applying a two-ply strip

to insoles, the combination of means for introducing a core, mechanism including a folder and a pair of presser members for forming one ply of the strip about the core, mechanism independent of the rib-forming mechanism for applying the other ply of the strip to an insole and for feeding the strip and insole, and means for operating said rib-forming and applying mechanisms in timed relation.

33. In a machine for applying a strip to insoles, said strip comprising a plurality of layers secured together along their mid portions, means for folding the marginal portions of one of the layers toward each other, means for introducing a cord between said portions as they are folded, means for forming the folded portions about the cord, means for supporting an insole, and means for pressing the marginal portions of an unfolded layer of the strip against the marginal portion of the insole.

34. In a machine for applying a strip to insoles, said strip comprising a plurality of layers secured together along their mid portions, mechanism for presenting a core piece adjacent to said strip and for folding one layer of the strip about the core piece, mechanism independent of said strip-forming mechanism for applying another layer of the strip to the marginal portion of an insole and for feeding said strip and insole, and means for operating said mechanisms in timed relation.

35. In a machine for applying a strip having a plurality of plies to insoles, the combination of means for introducing a core, means for folding one ply of the strip about the core to form a rib, means for supporting an insole, means for applying another ply of the strip to the insole, means for feeding the insole, and means for feeding the strip, said feeding means being operated in timed relation and the strip-feeding means operating to feed the strip faster than the insole-feeding means feeds the insole.

36. In a machine for applying a composite strip to insoles, said strip comprising a plurality of layers secured together along their mid portions, the combination of mechanism for turning the marginal portions of one of the layers toward each other, for introducing a core piece between said portions, for pressing said portions together to envelop said core piece, and for feeding the strip so formed, mechanism independent of said strip-forming mechanism for applying another layer of said strip to the marginal portion of an insole and for feeding the strip and insole, and means for operating said mechanisms in timed relation.

37. In a machine for applying a composite strip to insoles, said strip comprising a plurality of layers secured together along their mid portions, means for introducing a core piece, means for folding one layer of the strip about the core piece, a pair of rolls for pressing the folded layer about the core piece, means for supporting an insole, a guide for presenting the strip adjacent to the margin of the supported insole, means on the guide for feeding the insole, means on the guide for feeding the strip, means for operating the guide to feed the strip and insole, means for pressing the unfolded layer of the strip against the margin of the insole, and means for operating said rolls and said strip guide in timed relation.

38. In a machine for applying a strip to insoles, said strip comprising a plurality of layers secured together along their mid portions, means

for folding the marginal portions of one of the layers toward each other, means for introducing a cord between said portions as they are folded, means for forming the folded portions about the cord, means for supporting an insole, means for presenting the marginal portions of an unfolded layer of the strip adjacent to the marginal portion of the insole, and means for pressing said marginal portions of the strip against the marginal portion of the insole.

10 39. In a machine for forming a ribbed strip for application to insoles, said strip comprising a plurality of layers secured together along their mid portions, the combination of a guide to receive one layer of the strip, means for turning the marginal portions of another layer toward each other, and means for pressing said marginal portions together to form a ribbed strip.

20 40. In a machine for forming a ribbed strip for application to insoles, said strip comprising a plurality of layers secured together along their mid portions, the combination of a guide to receive one layer of the strip, means for turning marginal portions of another layer toward each other, and a pair of rollers for pressing said marginal portions together to form a ribbed strip.

25 41. In a machine for forming a ribbed strip for application to insoles, said strip comprising a plurality of layers secured together along their mid portions, the combination of a guide to receive a base layer of the strip, a pair of plows for turning marginal portions of another layer toward each other, a pair of rollers for pressing said marginal portions together to form a ribbed strip, and means for turning the rollers to feed the strip.

30 42. In a machine for forming a ribbed strip for application to insoles, said strip comprising a plurality of layers secured together along their longitudinal central portions, the combination of a guide for a base layer of the strip, a pair of plows for turning the marginal portions of another layer of the strip away from the base layer, means for introducing a core piece between said marginal portions, and means for pressing said marginal portions against the core piece to form a rib on said base layer.

35 43. In a machine for forming a ribbed strip for application to insoles, said strip comprising a plurality of layers secured together along their longitudinal central portions, the combination of a guide for a base layer of the strip to hold it in flat condition, a pair of plows for turning the marginal portions of another layer of the strip away from the base layer, means for introducing a core piece between said marginal portions, and a pair of rolls for pressing said marginal portions against the core piece to form a rib on said base layer.

40 44. In a machine for forming a ribbed strip for application to insoles, said strip comprising a plurality of layers secured together along their longitudinal central portions, the combination of a guide for a base layer of the strip, a pair of plows for turning up the marginal portions of another layer of the strip, means for introducing a core piece between said marginal portions, a pair of rolls for pressing said marginal portions against the core piece to form a rib on said base layer, and means for turning the rolls to feed the strip.

45 45. In a machine for applying a strip having a plurality of plies to insoles, the combination of means for forming plies of the strip into a rib, mechanism for applying another ply of the

strip to the insole, said means comprising a roll for continuously pressing one marginal portion of the strip on the insole, and an intermittently operating hammer acting to apply the other marginal portion of the strip to the insole.

46. In a machine for applying a ribbed strip to insoles to form a sewing rib thereon, the combination of a support for an insole, a strip guide, means carried by the strip guide for feeding the strip, means carried by the strip guide for feeding the insole, means for imparting a four-motion movement to the strip guide, a roll for continuously pressing one marginal portion of the strip on the insole, and intermittently acting means for pressing the other marginal portion against the insole.

47. In a machine for applying ribbed strips to insoles, the combination of means for supporting an insole, means for feeding the strip and insole, means for feeding the strip to the insole, a roll for causing continuous pressure to be applied to one marginal portion of the strip, and a reciprocating foot for applying intermittent pressure to the other marginal portion of the strip.

48. In a machine for applying composite strips to insoles to form a sewing rib thereon, the combination of means for supporting an insole, means for presenting a strip adjacent to the marginal portion of the insole, feeding means engaging the strip, feeding means engaging the insole, means for operating said feeding means in unison, and a hammer for beating the inner marginal portion of the strip against the insole, said hammer having a component of movement directed outwardly of the insole.

49. In a machine for applying ribbed strips to insoles, the combination of a rotary table adapted to support an insole, a strip guide for presenting a ribbed strip to the marginal portion of the insole, a feed member on said guide for feeding the strip, a second feed member on said guide to engage the insole, means for imparting a four-motion movement to said guide to feed the strip and insole, means for causing more of the feed movement to be imparted to the strip than is imparted to the insole, means for rolling one marginal portion of the strip against the insole, and means for intermittently beating the other marginal portion of the strip against the insole.

50. In a machine for applying ribbed strips to insoles, the combination of a rotary table adapted to support an insole, a strip guide for presenting a ribbed strip adjacent to the marginal portion of the insole, feed fingers mounted in said guide above the strip for feeding the strip, a feed foot on the lower face of said guide for engaging the insole, means for operating the guide to feed the strip and the insole, a yieldingly mounted roll for continuously pressing one marginal portion of the strip against the insole, and a yieldingly operated hammer to beat the other marginal portion of the strip against the insole.

51. In a machine for applying ribbed strips to insoles to form sewing ribs thereon, the combination of means for supporting an insole, a guide for presenting a strip to the marginal portion of the insole, means for imparting a four-motion movement to the guide, means on the guide for moving the strip only in the direction of feed, means on the guide to engage and feed the insole during its feed movement, means for causing the insole-feeding means to engage the insole only

after part of the movement of the strip guide has been effected thereby causing filling of the strip as it is applied to the insole, a roll acting continuously yieldingly to press the outer marginal portion of the strip upon the marginal portion of the insole, and a yielding hammer arranged to beat the inner marginal portion of the strip against the insole, said hammer having a component of movement directed outwardly with respect to the insole.

52. In a machine for applying ribbed strips to insoles to form a sewing lip thereon, the combination of a support for the insole, means for applying the ribbed strip to the insole, a gage for engaging the edge face of the insole, a plurality of stops for the gage, and means for shifting the gage against said stops in turn without interrupting the operation of the machine to cause the strip to be applied to the insole at different predetermined distances from the edge thereof.

53. In a machine for applying ribbed strips to insoles to form a sewing lip thereon, the combination of a support for the insole, means for feeding the strip and insole, means for progressively applying the ribbed strip to the insole, a gage for engaging the edge face of the insole, adjustable stops for limiting movement of the gage, and means operable while the machine is in operation for shifting the gage as the operation progresses against said stops in turn to cause the strip to be applied to the insole at different predetermined distances from the edge thereof.

54. In a machine for applying ribbed strips to insoles to form a sewing lip thereon, the combination of a support for the insole, means for progressively applying a strip to the insole adjacent to the edge thereof, a shiftable gage for engaging the edge face of the insole to determine the position of the strip with respect to the edge of the insole, a plurality of stops for the gage, and means for shifting the gage against said stops in turn during the operation of the machine to cause the strip to be applied to the insole at different distances from its edge during the application of the strip to the insole.

55. In a machine for applying ribbed strips to insoles to form a sewing lip thereon, the combination of a support for the insole, a guide for the strip, means carried by the guide for feeding the strip and insole, means for progressively applying the strip to the insole adjacent to the edge thereof, a shiftable gage for engaging the edge face of the insole, a plurality of stops for the gage, and a hand lever for shifting the gage, during the operation of the machine, against said stops in turn to cause the strip to be applied to the insole at different predetermined distances from its edge during the application of the strip to the insole.

56. In a machine for applying strips to insoles, the combination of a support for the insole, a guide for presenting a strip to the insole, means for feeding the insole, and means acting on the strip in each insole-feeding cycle before the strip engages the insole for feeding the strip faster than the insole is fed.

57. In a machine for applying strips to insoles, the combination of a support for the insole, a guide for presenting the strip to the insole, means for feeding the insole, and means acting on the strip in each insole-feeding cycle before the strip engages the insole for feeding the strip

faster than the insole is fed to relieve tension on the strip and cause the strip to be applied without distorting the insole.

58. In a machine for applying strips to insoles, the combination of a support for the insole, a guide for presenting the strip to the insole, means for feeding the insole, means operating in each insole-feeding cycle for feeding the strip a distance greater than the insole is fed to relieve tension on the strip and cause the strip to be fulled relatively to the insole, and means

for pressing the strip upon the insole to effect adhesion between the strip and insole.

59. In a machine for applying ribbed strips to insoles, the combination of means for supporting an insole, means for feeding the insole, means operating in each insole-feeding cycle for feeding the strip faster than the insole is fed, and means for applying pressure to the strip on opposite sides of the rib to attach the strip to the insole.

FREDERIC E. BERTRAND.
